Warren D. House
His ATTORNEY

UNITED STATES PATENT OFFICE.

WILLIAM LINK, OF TULSA, OKLAHOMA, ASSIGNOR OF ONE-THIRD TO OTHO G. ALLISON AND ONE-THIRD TO MAX HURST, BOTH OF KANSAS CITY, MISSOURI.

DIESTOCK.

Specification of Letters Patent. Patented Sept. 28, 1920.

1,354,316.

Application filed January 11, 1918. Serial No. 211,416.

To all whom it may concern:

Be it known that I, WILLIAM LINK, a citizen of the United States, residing at Tulsa, in the county of Tulsa and State of Oklahoma, have invented a certain new and useful Improvement in Diestocks, of which the following is a specification.

My invention relates to improvements in die stocks.

10 The object of my invention is to provide a die stock with novel oiling means, and which is simple in construction, cheap to manufacture, not liable to get out of order, which is efficient in operation, and which is 15 adapted for oiling dies of different diameter.

The novel features of my invention are hereinafter fully described and claimed.

In the accompanying drawing, which illustrates the preferred embodiment of my invention,

20 Figure 1 is a side elevation of my improved die stock.

Fig. 2 is a plan view of the same.

Fig. 3 is an enlarged longitudinal section 25 of a part of the die stock.

Fig. 4 is a longitudinal section, further enlarged, of a part of the oil conductor, and showing in elevation, a part of the outlet valve.

30 Similar reference characters designate similar parts in the different views.

1 designates the body of an ordinary revoluble die stock having the usual means for holding a die 2.

35 The die stock is provided with the usual diametrically opposite handles 3 and 4 disposed radially with respect to the body 1.

The handle 4 comprises a radially disposed tube externally screw-threaded at its 40 ends, the inner end being fitted detachably in a threaded socket 5, and the outer end being provided with an internally threaded collar 6.

45 The tubular or hollow handle 4 is provided with an air inlet and an oil outlet at its outer and inner ends respectively.

Connected with the outlet is an oil conductor comprising the following described parts.

50 An externally screw-threaded tube 7, Fig. 3, and Fig. 4, is fitted in a screw-threaded hole in the socket 5 located axially and radially with respect to the longitudinal center of the handle 4.

The inner end of the tube 7 is fitted in a screw-threaded sleeve 8, in which is also fitted the outer end of an externally threaded screw 9, on the inner end of which is fitted a cap 10, in which is secured the outer end of a right-angled tube 11, which forms the discharge portion of the conductor, and which has its outer end disposed in the die 2, as shown in Fig. 3.

By radially adjusting the tube 7 and sleeve 8, the discharge tube 11 may be moved 65 radially so as to properly adjust it for oiling dies of different sizes. The outer end of the tube 7 is preferably extended beyond the outer end of the socket 5, so that it may be readily gripped, when the handle 4 is detached from the socket 5, for turning it to its proper position in the socket.

For closing the outer end of the handle 4, an externally threaded plug 12 is fitted in the threaded outer end of the tube 7. The plug 12 is provided with an air inlet comprising a transverse hole 13, which is normally closed by means of a preferably inwardly opening self-closing valve 14 adapted to bear against the inner side of the plug 12 and provided with a stem 15 which extends through the hole 13 and has mounted on it a collar 16, against which bears the outer end of a coil spring 17, which encircles the stem 15, and which has its inner 85 end bearing against the outer side of the plug 12. The spring 17 normally forces the valve 14 to the closed position.

For normally closing the outlet of the handle 4 for controlling the flow through the conductor, I provide a preferably self-closing valve 18, which is mounted in the sleeve 8 and is adapted to bear against the inner end of the tube 7, which forms a seat for the said valve.

95 The valve 18 is provided with an axial stem 19, which extends through the tube 7 and is longitudinally slidably in a screw-threaded plug 20 which is fitted in a screw-threaded hole extending centrally through 100 the plug 12.

A coil spring 21 encircles the stem 19 and bears at its inner end against the outer end of the plug 20, and bears at its outer end against a thumb piece 22, which is secured 105 in the collar 6, within which the thumb piece is reciprocative, to the outer end of the stem 19.

- When the die stock is turned, in revolving, while cutting a thread, so that the handle 4 is at the top and in the vertical position, the operator may permit oil to flow 5 by gravity from the hollow handle 4, which forms the oil receptacle, through the conductor and into the die 2, by depressing the thumb piece 22, thereby forcing downwardly against the pressure of the spring 21, the 10 stem 19 and valve 18, so as to open the latter. The thumb piece 22 is of a diameter such that on its downward or inward movement, it will strike the outer end of the stem 15 and will depress the latter against the pressure of the spring 17, thus opening the valve 14 to permit entrance into the handle 4 of air to displace the oil which is discharged by gravity through the discharge conductor already described. When a sufficient amount 15 of oil has been discharged, the thumb piece 22 is relieved of pressure of the operator's thumb or finger, upon which the springs 17 and 21 will respectively force the valves 14 and 18 to closed position.
- 20 In order that the valve 18 shall not upon striking the outer end of the tube 9 shut off the flow of oil therethrough, the tube 9 is provided at its outer end with one or more notches 23, through which the oil can pass 25 from the sleeve 8 into the tube 9. The internal diameter of the sleeve 8 is greater than the largest diameter of the valve 18, thereby providing an annular space around the valve for the passage of oil.
- 30 The handle 4 adjacent to the socket 5 is provided with a filling hole which is screw-threaded and has detachably fitted in it a threaded plug 24.
- 35 For securing the valve 18 to the stem 19, the inner end of the stem is screw-threaded and has preferably mounted therein a lock 40

nut 25 which bears against the inner side of the valve 18, the outer side of which bears against a conical enlargement 26 with which the stem 19 is provided, said conical enlargement entering the tube 7 and serving as a guide for centering the valve upon the inner beveled end of the tube 7.

45 For holding the stem 19 from turning, when the valve 18 is being secured thereon, the thumb piece 22 may be provided with a peripheral notch 27 for receiving a screwdriver, or other suitable device, not shown, for holding the thumb piece from turning.

50 I do not limit my invention to the structure shown and described, as modifications, within the scope of the appended claim, may be made without departing from the spirit of my invention.

55 What I claim is:—

60 A die stock having a hollow handle adapted to form an oil receptacle and having an oil outlet at its inner end and at its other end having a removable closure provided with an air inlet, a conductor connected with said outlet and arranged to discharge into a die, a valve for closing said outlet having a stem slidably mounted in said closure, a thumb button attached to the outer end of said stem, a spring bearing 65 on said closure and against said button for closing said valve, a second valve for closing said air inlet having a stem normally disconnected with said button but adapted to be forced by the latter to the 70 open position when the button is forced to the open position, and a spring for normally closing said second valve.

75 In testimony whereof I have signed my name to this specification.

WILLIAM LINK.
